UNITED STATES PATENT OFFICE

2,132,661

SURFACING MACHINE

John C. Temple, New York, N. Y.

Application November 29, 1935, Serial No. 52,148

7 Claims. (Cl. 29—81)

This invention relates to improvements in surfacing machines for cleaning, brushing, scaling, or painting of metallic surfaces.

This invention like that set forth in my co-pending application Serial No. 46,995, filed October 28, 1935, has for its primary object the provision of a machine which utilizes electro-magnetic force for its support when the machine is in use for travel over vertical, or inclined surfaces for the cleaning, brushing, scaling, or painting of metallic surfaces, such as the sides of a sheet metal building, metal roofs, metal storage tanks, ship's hulls, and other like metallic structures.

An important object of this invention resides in a self contained, self motivated and remotely controlled surface treating machine involving the unique feature of combining mechanical principles for performing useful work, and simultaneously moving itself over metallic surfaces to which it is kept in continuous contact by means of electro-magnets attached to and forming a component part of the machine, and holding the machine to its work without interfering with its complete mobility.

This invention unlike that shown in my co-pending application is constructed on the caterpillar traction principle to provide a maximum magnetic tread contact between the machine and the metallic surface over which it is adapted to move.

Another feature of the invention resides in a caterpillar propelling mechanism wherein only those magnetic shoe treads which are in working contact with the metallic surface are energized, thus providing a rest period for the magnetized shoe treads as the same successively move into operative engagement with the metallic surface being worked upon.

Another feature of the invention is to provide a means for remotely and selectively controlling the operation of the machine and for obtaining flexibility in the guiding of the machine when in use.

A still further object is the provision of a machine having an electro-magnetic caterpillar propelling mechanism in which the magnetic shoe treads are air cooled to permit of the use of a maximum magnetic force without the danger of overheating.

With these and other objects in view, the invention resides in the certain novel construction, combination and arrangement of parts, the essential features of which are hereinafter fully described in the following specification, are par-

ticularly pointed out in the appended claims and are illustrated in the accompanying drawings, in which:

Figure 1 is a front elevational view of the machine with parts broken away.

Figure 2 is a side elevational view.

Figure 3 is a horizontal sectional view on the line 3—3 of Figure 1.

Figure 4 is an enlarged vertical transverse sectional view on the line 4—4 of Figure 1.

Figure 5 is a vertical transverse sectional view on the line 5—5 of Figure 1.

Figure 6 is a fragmentary horizontal sectional view on the line 6—6 of Figure 1.

Figure 7 is a fragmentary horizontal sectional view on the line 7—7 of Figure 1.

Figure 8 is a diagrammatic view showing the electrical circuits.

Referring to the drawings by reference characters, the numeral 10 designates a rectangular shaped chassis which includes a pair of spaced parallel channel side rails 11—11 and fixedly mounted in the side rails thereof are spaced transversely extending rods 12—12. The rods 12—12 serve to brace the chassis frame and serve as an axes for supporting certain rotatable mechanism presently to be described. Also extending transversely of the chassis frame adjacent the extreme ends of the rails 11—11 and journaled in bearings therein, are rotatable shafts 13—13, one of which has a rotatable surface scraping member 14 mounted thereon, whereas the other shaft 13 carries a surfacing element in the form of a rotary brush member 15. Whereas I have shown in the drawings the machine as being equipped with a rotary scraping member and a rotary brush member, it will be understood that these members may be interchangeable and a rotary painting member similar to that shown in the above mentioned application may be similarly used in this machine. Semi-circular shaped hood shields 16 enclose the respective work surfacing members.

Associated with the chassis 10 and disposed within the side rails 11—11 thereof, are two parallel caterpillar traction devices A and B which are identical in construction so that a description of one will suffice for the other. The caterpillar traction devices A and B are driven from a single motor 17, the armature shaft of which extends beyond opposite sides of the motor, and each end carries a pinion gear 18, the gears 18 respectively imparting power to the caterpillar traction devices A and B in the manner now to be explained.

Each caterpillar traction device includes a pair of sprocket disks 19-19 which are fixed to a tubular shaft or sleeve 20 which is rotatably mounted upon a fixed rod 12. An endless carrier member 21 which includes two separate sprocket chains, each chain formed of a plurality of pivotally connected links which pass around the spaced sprockets 19-19 carried by the rods 12-12 and pivotally supported by the link chains 10 of the endless carrier are closely spaced magnetic shoes 22. The pivotal axes of the shoes 22 which are in the form of pins are designated by the numeral 23 and they extend through certain of links of the endless carrier member and seat 15 in semi-circular shaped notches 24 provided in the sprocket disks 19 during passage of the endless carrier around the respective sprockets. For the purpose of guiding the flexible endless carrier 21 during its movement, spaced tracks in 20 the form of elongated plates 25 are provided, and the pins 23 carry rollers 26 for engagement with the respective tracks. It will of course be understood that the tracks 25 are rounded at their respective ends to conform to the circular 25 path taken by the endless carrier as it moves around the supporting sprockets.

Each of the caterpillar traction devices as previously mentioned is driven from the motor 17 and this driving mechanism includes a ring gear 30 27 fixedly connected to one of the sprocket disks 19 of the caterpillar traction device driven thereby. Journaled in a bearing 28 and extending transversely of the machine, is a counter-shaft 29 which carries at one end a pinion gear 30 35 which is in constant mesh with the ring gear 27. Splined to the countershaft 29 is a sleeve 31 carrying a pair of reversely arranged bevel pinion gears 32 for selective meshing engagement with the pinion gear 18. The splined sleeve is under 40 the influence of a solenoid 33 which when energized causes the splined sleeve 31 to be moved to cause one of the gears 32 to mesh with the pinion 18, and when the solenoid is deenergized, a spring 34 surrounding the counter-shaft and 45 interposed between one of the pinions 32 and an adjacent portion of the bearing 28, serves to move the splined sleeve in an opposite direction to cause the other gear 32 to be brought into meshing engagement with the pinion 18. By 50 the alternate shifting of the gears 32 into engagement with the pinion 18, it will be readily understood that the driven shaft 29 may be turned in either direction and by placing the solenoid 33 under the control of an operator, the shifting 55 of these gears may be remotely controlled as shown in Figure 8 and as will be presently explained.

Each electro-magnetic shoe 22 includes an electro-magnet having a rectangular shaped body 60 35 within which is arranged the north and south poles 36, the same being suitably insulated from the body 35. The electro-magnet also includes plates 37 which are connected with the respective poles 36 and are in contacting engagement 65 with a metallic tread plate 38. The poles 36 include contact buttons 39 which respectively engage parallel conductor rails 40. The conductor rails 40 are joined by yokes 41 adjacent their opposite ends and the said yokes are pivotally connected to levers 42 turnably mounted upon 70 transversely disposed shafts 43 fixedly mounted in the spaced guide track plates 25.

The ends of the conductor rails 40 are curved inwardly as at 44 and the rails are of such length 75 as to permit of contact of the magnetic shoes

therewith just prior to their movement into position with a contacting metallic surface and to break contact with the rails as the shoes move successively to a position out of contact with a metallic work surface. In view of the fact that the machine operates either up or down or back and forth without turning the same, it is necessary to shift the rails 40 to perform the function above mentioned. For this purpose, the conductor rails of each caterpillar traction device are 10 under the influence of a solenoid 45, the same being operatively connected with one of the levers 42. In Figure 5 the solenoid 45 is shown as energized and has moved the conductor rails upwardly as the machine is traveling upwardly in 15 the direction of the arrow but upon deenergizing of the solenoid 45, a spring 46 acts upon the lever 42 to move the rails in an opposite direction. The movement of the rails in opposite directions is limited by stop pins 47 disposed in 20 the path of the levers 42. It will thus be seen by the energizing and deenergizing of the solenoid 45, the position of the conductor rails may be placed under the selective control of an operator located at a remote point, and the solenoid 25 45 associated with the rails of one of the caterpillar traction devices is arranged in series and in the same circuit with the solenoid 33 controlling the direction of drive imparted to the other caterpillar traction device.

For the purpose of air cooling the electro-magnetic shoes, I associate with each caterpillar traction device, a motor driven fan 47, the motor 48 thereof being mounted upon a platform 49 supported by a side rail 11. The blades of the 35 fan are disposed within an opening 50 arranged in an outer track plate 25 as best seen in Figure 7 of the drawings, and during operation, a blast of air is directed inwardly between the shoes carried by both leads of the endless carrier.

For the purpose of imparting rotary movement to the work surfacing devices 14 and 15, the shafts 13-13 at one side of the chassis are provided with sprockets 51, and passing over the sprockets and disposed within the side channel rail 11 is an endless sprocket chain 52, the same being placed under tension to take up slack by an idler sprocket 53 journaled in the side rail and disposed approximately midway between the shafts 13-13. Extending from the side channel 45 rails 11-11 are bearings 54 in which a transversely disposed shaft 55 is journaled. The shaft 55 carries a gear 56 which is in meshing engagement with one of the pinion gears 30 whereby power is transmitted from the motor 17, to the shaft 29, gear 30, gear 56, to the shaft 55. Carried adjacent one end of the shaft 55 is a sprocket wheel 57 over which an endless sprocket chain 58 passes, the said chain also passing around a smaller sprocket 59 carried by one of the shafts 13. By the construction just described, one of the shafts 13 is operatively connected to the driven shaft 55 whereas the other shaft 13 receives its power through the sprocket chain 52 and sprocket wheels 51.

In Figure 8 of the drawings, I have illustrated a diagrammatic view of the electrical wiring system by which I am enabled to remotely control the operation of the machine during its use. In this view the motor control circuit V is controlled by the actuation of a switch 60 and arranged in the circuit V is the motor 17 and the fan motors 48. It will thus be seen that when the switch 60 is closed as shown in the drawings, the motors 17 and 48 will be placed in oper- 70 75 80 85 90 95 98

ation. The sets of rails 40 of the caterpillar traction devices A and B are arranged in an electric circuit X controlled by a switch 62 and by closing of said switch, current will be supplied to the sets of rails 40 which are bridged by the tread plates 38 through the contact buttons 39.

Control circuits Y and Z are substantially identical and both include a control switch 61 in the circuit, the conductor rail controlling solenoid 45 10 of one of the caterpillar traction devices, and the solenoid 33 of the other solenoid traction device. By the operation of the control switches 60 and 62, the machine may be placed in condition for 15 operation and by the selective control of the switches 61, the caterpillar traction devices may be operated simultaneously in the same direction or simultaneously in opposite directions in order to provide flexibility for guiding the machine over a surface being worked upon.

20 During operation of the machine, it will be understood that the electro-magnetic force set up by the magnetic shoes will serve to support the machine in a vertical or inclined position upon the metallic surface being worked against the 25 force of gravity, the flat magnetized tread plates 38 flatly engaging such metallic surface. By reference to Figure 5, it will be seen that at least three magnetic shoes are at all times in contact with the metallic surface, the magnetic force of 30 which is sufficient to cause the machine to be supported in operating position. By reason of the selective control of the two caterpillar traction devices, it is possible to selectively move the machine up or down, or back and forth, or to 35 turn the same within its length by the operation of one of the caterpillar traction devices in one direction and reversing the direction of operation of the other caterpillar traction device. During 40 operation of the machine, it will be seen that the work surfacing devices 14 and 15 contact the surface being worked upon for either scraping and brushing the same as shown in the drawings, or by the substitution of a paint brush attachment which might be used in lieu thereof.

45 Whereas I have shown and described what I consider to be the most practical embodiment of my invention, I wish it to be understood that such changes and alterations as come within the scope of the appended claims may be resorted to 50 when desired.

Having thus described the invention, what I claim as new and desire to secure by Letters Patent of the United States, is:—

1. A machine for use upon vertical or inclined 55 metallic surfaces comprising in combination, a chassis, two separate magnetic caterpillar traction devices arranged in spaced parallel relation, an electric motor mounted on said chassis, individual driving means operable by said motor 60 for operating the respective magnetic caterpillar traction devices in either direction, and means for selectively controlling the direction of operation of the individual driving means to facilitate the guiding of the machine over a metallic surface over which it is adapted to travel.

2. In a machine of the class described, a chassis, a magnetic caterpillar traction device including spaced rotatable sprockets, an endless flexible carrier passing over said sprockets, electro-magnetic 70 traction shoes flexibly connected to said endless carrier, the shoes extending along one lead of said endless carrier adapted to have their outer sides operatively contact a metallic surface, a pair of spaced fixed conductor rails carried by 75 said chassis and extending parallel to and in-

wardly of the above mentioned lead on said endless carrier, and pairs of pick up contacts on the inner sides of said shoes for wiping engagement with the respective conductor rails.

3. In a machine of the character described, a 5 chassis, a magnetic caterpillar traction device for said chassis including a driven endless carrier, a plurality of magnetic shoes mounted on said endless carrier, means for electrically energizing the magnetic shoes as they engage a metallic surface with which they are adapted to frictionally contact, and a motor driven fan disposed adjacent one side of said endless carrier for directing a current of air inwardly over said magnetic shoes for cooling the same during operation. 10 15

4. A surfacing machine for use upon metallic surfaces comprising in combination, a chassis, electro-magnetic traction means for said chassis including two spaced parallel magnetic caterpillar devices mounted on said chassis, means for 20 simultaneously energizing both of said magnetic caterpillar devices, means for driving said magnetic caterpillar devices in forward or reverse directions, a pair of rotatable surface work devices journaled transversely in said chassis and 25 disposed respectively at opposite ends of said chassis, and means for simultaneously rotating said surface working devices in either direction.

5. In a machine of the class described, a chassis, a magnetic caterpillar traction device including spaced rotatable sprockets, means for selectively rotating said sprockets in opposite directions, an endless flexible carrier passing over said sprockets, electro-magnetic traction shoes 30 flexibly connected to said endless carrier, the 35 shoes extending along one lead of said endless carrier adapted to have their outer sides operatively contact a metallic surface, a set of spaced conductor rails supported by said chassis and movable relative thereto for a limited longitudinal movement, said rail being disposed inwardly of the above mentioned lead of said endless carrier and parallel thereto, pairs of pick up contacts 40 on the inner sides of said shoes for wiping engagement with the respective conductor rails, and 45 means for shifting said conductor rails longitudinally in accordance with the selected direction of rotation of said sprockets to cause a magnetic shoe which is about to enter the active lead of the carrier to engage said conductor rails and 50 to cause a shoe leaving said lead to break free of said conductor rail just prior to its disengagement with a metallic surface.

6. In a machine of the class described, a chassis, a magnetic caterpillar traction device for said 55 chassis including a driven endless carrier, a plurality of electro-magnetic shoes mounted on said endless carrier, and fan means for directing cooling air between the leads of said endless carrier for cooling said electro-magnetic shoes to prevent 60 overheating of the same during operation of the machine.

7. A machine for use upon vertical or inclined 65 metallic surfaces comprising in combination, a chassis, two separate magnetic traction devices arranged in parallel relation, a power unit mounted on said chassis, individual driving means operable by said power unit for operating the respective magnetic traction devices in either direction, and means for selectively controlling the 70 direction of operation of the individual driving means to facilitate the guiding of the machine over a metallic surface over which the machine is adapted to travel.
